SHOE AND SHOE BOTTOM PARTS

Horatio S. Lyness, Lynn, Mass., assignor to United Shoe Machinery Corporation, Borough of Flemington, N. J., a corporation of New Jersey

Application March 26, 1940, Serial No. 326,035

13 Claims. (Cl. 36—76)

This invention relates to improvements in shoes and to improvements in insole units and shank pieces for shoes.

It is a well-known practice to reinforce the heel and shank portion of an insole by means of a heel and shank piece of fabricated sheet material such as fiberboard which is coextensive with that portion of the insole and is secured to the lower side thereof by means of an adhesive such as rubber cement. Such reinforcement of the insole, however, is usually insufficient to provide the requisite stiffness and strength in the shank portion of the shoe bottom and means such as a conventional shank stiffener of metal or wood is commonly used in conjunction with the reinforcing piece either in the process of making an insole unit or later in the course of the manufacture of the shoe. Moreover, in some types of shoes undesirable conditions may result because of insufficient security of attachment of the reinforcing piece to the insole.

Objects of the present invention are to provide increased strength and stiffness in the shank portion of a shoe having a reinforced insole of the type above referred to without the use of a conventional shank stiffener or similar device and to insure that the reinforcing means will remain securely attached to the insole regardless of any forces tending to separate these elements during the wearing of the shoe in which they are incorporated.

As herein illustrated these objects have been accomplished, in accordance with one aspect of my invention, by providing a plurality of perforations in a shank reinforcing piece and securing the shank piece to an insole by means of a continuous body of hardened cementing and stiffening material comprising a mass of substantial thickness which is located between the shank piece and the insole and a series of stud-like projections formed integrally upon said mass which extend into the perforations in the shank piece. This body of hardened cementing and stiffening material with its stud-like projections not only firmly and permanently secures the reinforcing piece to the insole but also, because of the inherent stiffness of the hardened material, strengthens and reinforces the shank portion of the insole to such an extent that it becomes unnecessary to employ a metallic stiffener or other shank stiffening means of a like nature to insure the desired stiffness in the shank portion of the shoe bottom.

My invention is particularly useful in the manufacture of open-shank shoes having cement-attached outsoles, since in such shoes there is no

overlasted upper margin upon the shank portion of the insole to which the outsole can be cemented and therefore, in the shank portion of the shoe, the outsole is cement-attached only to the shank reinforcing piece. For use particularly in such shoes, as herein illustrated, the continuous body of hardened cementing and stiffening material which secures the reinforcing piece to the insole includes a mass of substantial thickness which overlies the lower side of the reinforcing piece as well as the upper side thereof and which is integrally connected with the mass at the upper side of the reinforcing piece by the stud-like portions which extend through the perforations in the reinforcing piece. The mass of cementing and stiffening material between the reinforcing piece and the outsole bonds the outsole directly to the reinforcing piece in the shank portion of the shoe and adds substantially to the stiffness and strength of the shank portion of the shoe bottom. In addition, the shank portion of the outsole is secured directly to the insole by the body of cementing material where the perforations in the reinforcing piece are located. The stud-like portions of the body of cementing material within the perforations in the reinforcing piece are particularly important in open-shank shoes where, as herein illustrated, the shank reinforcing piece is of laminated formation because they serve to tie or bind together the several layers of the reinforcing piece so that they will not separate and thus weaken the attachment of the shank portion of the outsole to the shoe. When such a laminated reinforcing piece is employed the cementing and stiffening material, which may be applied in a softened state to the reinforcing piece, will not only fill the perforations in the latter but will spread outwardly short distances between the layers thereof and thus, when it has become hardened, flange-like projections or fins are formed around the stud-like members which fill the perforations and these fins securely anchor the stud-like members in place and contribute to the security of attachment of the various parts which constitute the shank portion of the shoe bottom.

The invention will be explained with reference to the accompanying drawing, in which

Fig. 1 is a bottom plan view of my improved insole unit;

Fig. 2 is a perspective view of the heel and shank reinforcing piece employed in the insole unit;

Fig. 3 is a view, partially in side elevation and partially in longitudinal section, of a completed open-shank shoe embodying the insole unit;

Fig. 4 is a bottom plan view of the shoe as it appears before the outsole has been applied;

Fig. 5 is a sectional view taken along the line V—V of Fig. 1; and

Fig. 6 is a cross-sectional view of the completed shoe, the section being taken through the open-shank portion of the shoe.

Referring to the drawing, my improved sole unit comprises a full length insole 10 and a heel and shank reinforcing piece 12 which is secured to the lower side of the insole, i. e., to the side which is to face the outsole of the shoe. The reinforcing piece 12 is shaped by a die-cutting or other operation to correspond in marginal contour with that of the heel and shank portion of the insole so that the reinforcing piece will be coextensive with that portion of the insole when applied thereto. The reinforcing piece may be composed of fiberboard or other fabricated material and, as shown, it consists of a piece of fabricated sheet material of laminated formation comprising a plurality of layers 14 (Fig. 5) which are more or less firmly held together so as to provide a unitary piece but which, nevertheless, have a distinct tendency to become separated when the piece is subjected to strains such as it would be subjected to when in the bottom of a shoe. In order positively to prevent the component layers of the reinforcing piece from separating during the wearing of the shoe, I form in the reinforcing piece a plurality of perforations 16 (Fig. 2), each of which extends entirely through all of the layers, and I introduce into these perforations cementing and stiffening material such as pyroxylin, the material being applied in a softened or activated state, as by means of a brush or the nozzle of a cement applying machine, so that it will completely fill the perforations, in which case it will spread or flow outwardly more or less into the areas between the layers in the immediate vicinity of the perforations. Thus, when the material becomes hardened, it will form solid studs or rivet-like members 18 having integral flange-like projections 19 which extend between the layers 14 so that the layers are securely held or tied together by means of the hardened cementing material in much the same manner as if the layers were riveted together. Advantageously the pyroxylin will be plasticized so that when hardened it will have substantially the resiliency of the usual wood or metal shank stiffener. Preferably, as shown, a row of perforations 16 is formed along each lateral margin of the shank piece and advantageously other perforations may be formed in other portions of the shank piece, as may be found desirable, to increase the security of attachment of the layers. The perforations may be overfilled with the cementing material so that the stud-like fillings will overlap more or less the upper and lower sides of the reinforcing piece and thus function as rivet heads to hold the upper and lower layers in place. However, as illustrated, I prefer to apply the cementing and stiffening material so that, in addition to filling the perforations, the upper and lower surfaces of the reinforcing piece will be overlaid with cement coatings or layers 20 and 22, respectively, as indicated in Fig. 5. These layers 20 and 22, as shown, are of substantial thickness, the layer 20 extending to the edge of the reinforcing piece while the layer 22 preferably stops short of the edge to facilitate the application of an edge binding strip to the lower

marginal surface of the piece after the piece has been secured to an insole. After a plurality of reinforcing pieces have been prepared as above described and the cementing material applied to each piece has become hardened, a suitable solvent is applied to the layer 20 at the upper side of the piece and also to a hardened coating of the same kind of cement previously applied to the insole and the reinforcing piece is laid in position upon the insole and the parts are placed between appropriately shaped molding forms in a press where the parts are maintained under pressure until the cementing material has hardened and the parts have been firmly and permanently secured together to provide a molded insole unit. The forms will impart the desired amount of longitudinal curvature to the shank portions of the insole and the reinforcing piece so that the shank portion of the insole unit will conform to the longitudinal curvature of the bottom of a foot, the amount of curvature being, for example, as indicated in Fig. 3. The molding forms are also preferably shaped to mold the insole unit transversely as indicated in Fig. 5.

Under the influence of the molding and attaching pressure the cement coating upon the insole will coalesce with the layer 20 upon the upper surface of the reinforcing piece so that a continuous body of hardened cementing and stiffening material will be provided between the insole and the reinforcing piece, this body extending also into and filling the perforations in the reinforcing piece and overextending the lower surface of the piece. This body of material will serve not only to bind together the component layers of the laminated reinforcing piece and securely to attach the reinforcing piece to the insole, but also, because of its inherent stiffness, it will stiffen and strengthen the shank portion of the insole unit. After the cementing material has hardened and the insole unit has been removed from the press, an edge binding will be applied to the unit to adapt it for use in an open-shank shoe. The edge binding may consist of a strip of suitable binding material, such as the strip 24, and it is applied so as to cover the edges and the adjacent exposed margins of both the insole and the reinforcing piece in the shank portion of the unit. The binding strip 24 may be secured in place solely by means of adhesive, as indicated in the drawing, or it may be attached by means of stitches. Insole units constructed as above described may be manufactured at reduced cost inasmuch as it is unnecessary to assemble a shank stiffener with the other parts to secure the shank stiffener in place and the resulting insole unit will be exceptionally light in weight and the component parts thereof will be bonded together in such a manner that there will be no liability of their becoming separated during the wearing of the shoe. Moreover, the insole and reinforcing piece having been curved longitudinally and transversely as determined by the shapes of the operating surfaces of the molding forms, the body of cementing and stiffening material when hardened will be correspondingly curved and because of its inherent stiffness and the fact that it is coextensive in width and length with that of the insole unit it will serve permanently to retain the curved shape of the unit.

Instead of utilizing pyroxylin as the cementing and stiffening material, I may employ sheet Celluloid or other substances which are capable of being softened into a plastic or semiplastic

state and thereafter becoming hardened to provide the desired strength, stiffness and resiliency for reinforcing the shank portion of a shoe so that the curvature thereof will be retained throughout the life of the shoe. An example of another such substance comprises a base of cotton or wool fiber treated with a cellulose compound, such material becoming plastic, adhesive and readily moldable when subjected to the action of a solvent, such as acetone, and subsequently, upon evaporation of the solvent, hardening into a solid mass which although stiff and strong is also resilient. In using such material, or in using sheet Celluloid, it may be applied in semiplastic sheet form and forced into the perforations in the reinforcing piece by the pressure utilized in securing together and molding the parts of the insole unit.

In making a shoe embodying my improved insole unit the margins of the upper materials are secured in overlasted positions upon the lower side of the insole either on or off a last and thereafter an outsole 28 is laid and attached to the shoe. As illustrated herein with respect to the manufacture of an open-shank shoe an upper forepart or vamp 30 and a separate back part 32 are assembled with the reinforced insole and the lower margins of these parts are secured in overlasted positions upon the forepart of the insole and upon the heel portion of the reinforcing piece respectively by means of tacks 34. The cementing material upon the lower side of the reinforcing piece is utilized in attaching the outsole and preferably the forepart of the outsole is likewise attached by cement. Accordingly, the outsole may be prepared for attachment in the usual way by having a coating of pyroxylin cement applied to and allowed to dry upon a previously roughened marginal surface of the outsole and likewise a coating of cement is applied to and allowed to dry upon the overlasted margin of the upper, the latter, however, being present only in the forepart and heel portions of the shoe if an open-shank shoe is being made. Just prior to the attachment of the outsole solvent is applied to the cement coatings on the outsole and on the upper and also to the layer of cementing material upon the lower side of the reinforcing piece if that layer has been permitted to harden after having been applied. The outsole is laid in place upon the shoe bottom and the shoe is placed in a cement sole attaching press. The softened cement coating upon the shank portion of the outsole will coalesce with the softened layer or mass of cementing material upon the lower side of the reinforcing piece and the shoe is allowed to remain in the press until the plastic mass has hardened. When the shoe is removed from the press, the outsole will be securely attached by the hardened cement. A heel 36 is then attached by means of nails 38 driven from the inside of the shoe and a sock lining 40 is cemented in place to cover the foot-facing side of the insole.

In the shank portion of the bottom of the shoe, made as above described, there will be a hardened body of cementing and stiffening material extending between the shank reinforcing piece and the insole, and between the reinforcing piece and the outsole, and filling the perforations in the reinforcing piece. This continuous body of material runs together in a unitary structure, all the component parts of the shank portion of the shoe bottom positively and permanently securing the reinforcing piece to the in-

sole and the outsole to the reinforcing piece as well as binding together the component layers constituting the reinforcing piece so that they cannot become separated during the wear of the shoe or permit the shank portion of the outsole to pull away from the shoe bottom. Because of the hard, stiff nature of this continuous body of material, it stiffens and permanently retains in foot-conforming shape the entire shank portion of the shoe bottom so that no conventional shank stiffening means, such as a metallic or wooden shank stiffener, is required to preserve the shape of the shoe bottom, and to provide adequate support for the arched portion of the foot. Inasmuch as the perforations in the reinforcing piece, which receive portions of the body of stiffening material, are located principally along the opposite lateral margins of the shank portion of the piece, the marginal portions of the shoe bottom will be stiffened and bound together so that they will not break down under the weight of the foot but will be supported much more effectively than they would be in a shoe with a conventional relatively narrow shank stiffener located in the central shank portion of the shoe bottom. The present construction is particularly useful in open-shank shoes where there is no overlasted upper margin between the shank portions of the inner and outer soles and where, consequently, there are no metallic or other lasting fastenings extending into the reinforced insole to assist in securing the reinforcing piece to the insole and holding together the layers of the reinforcing piece.

Having described my invention, what I claim as new and desire to secure by Letters Patent of the United States is:

1. A shank piece comprising a plurality of layers of sheet material arranged in face-to-face relation, said piece having a plurality of perforations each extending through all of said layers, and stud-like members of hardened cementing material in said perforations positively securing said layers together.
2. A shank piece comprising a plurality of layers of sheet material arranged in face-to-face relation, said piece having a plurality of perforations each extending through all of said layers, and rivet-like members of hardened cementing material filling said perforations and having flange-like projections extending between said layers in the immediate vicinity of said perforations.
3. A shank piece comprising a plurality of layers of sheet material arranged in face-to-face relation, said piece having a plurality of perforations each extending through all of said layers, and a continuous body of hardened cementing and stiffening material overlying one side of said piece and filling said perforations.
4. A shank piece comprising a plurality of layers of sheet material arranged in face-to-face relation, said piece having a plurality of perforations each extending through all of said layers, and a continuous body of hardened cementing and stiffening material overlying both sides of said piece and filling said perforations.

5. An insole unit comprising an insole, a shank reinforcing piece having a plurality of perforations therein, and a continuous body of hardened cementing and stiffening material between said parts permanently uniting them to provide an insole unit, said body also filling said perforations, thereby providing additional stiffness

in the shank portion of the unit and increasing the security of attachment of said parts.

6. An insole unit comprising a full length flexible insole, a shank reinforcing piece having a row of perforations extending along each lateral margin thereof, and a continuous body of hardened cementing and stiffening material between said parts securing them together to provide an insole unit having a flexible forepart and a shank portion of substantial stiffness, said body having projecting portions extending into said perforations, thereby providing additional stiffness in the marginal shank portions of the unit and increasing the security of attachment of the reinforcing piece to the insole.

7. An insole unit comprising an insole, a shank reinforcing piece consisting of a plurality of layers of sheet material and having a plurality of perforations each extending through all of said layers, and a continuous body of pyroxylin cement between the insole and the reinforcing piece securing said parts together, said body extending also into said perforations and between said layers and securing said layers together.

8. A molded insole unit comprising an insole having a longitudinally and transversely curved shank portion, a reinforcing piece coextensive with the shank portion of the insole, said piece being curved to correspond to the curvature of the shank portion of the insole and having a plurality of perforations therein, and a continuous body of hardened cementing and stiffening material securing said parts together and preserving their molded form, said body comprising a layer of substantial thickness between the insole and the reinforcing piece and extending throughout the full length and width of the shank portion of the insole, and portions integral with said layer filling said perforations and overextending the outer surface of the reinforcing piece.

9. An insole unit comprising an insole, a plurality of layers of sheet material disposed in face-to-face relation at one side of the shank portion of said insole, each of said layers having a plurality of perforations therein, the perforations in one layer being aligned with corresponding perforations in the next adjacent layer, and a continuous body of hardened cementing and stiffening substance extending between said body also filling the aligned perforations in the insole and the adjacent layer of reinforcing material and securing said parts together, said layers and extending between said layers in the immediate vicinity of said perforations, thereby securing said layers to one another and to the insole.

10. An insole unit for use in open-shank shoes comprising an insole, a shank reinforcing piece coextensive in width and length with that of the shank portion of the insole secured to one

side of the insole and having a row of perforations extending lengthwise of said piece in each marginal portion thereof, and a layer of hardened cementing and stiffening material between the insole and the reinforcing piece, said layer having projections formed integrally therewith and extending into said perforations.

11. An insole unit for use in open-shank shoes comprising an insole, a shank reinforcing piece coextensive in width and length with that of the shank portion of the insole secured to one

side of the insole and having a row of perforations extending lengthwise of said piece in each marginal portion thereof, an edge binding covering the edges of said piece and the insole and overlying the adjacent outer surface portions of these parts, a layer of hardened cementing and stiffening material covering the lower side of said piece inwardly of said edge binding, a layer

of said material between said piece and the insole securing said parts together, and stud-like filler members integral with the material of each of said layers extending through the perforations in said piece.

12. A shoe comprising an insole, a heel and shank reinforcing piece located beneath the insole and having a plurality of perforations in its shank portion, an upper having its lower margin secured in overlasted position upon the insole, an outsole, a continuous body of hardened cementing and stiffening material extending through the perforations in the reinforcing piece and extending between the reinforcing piece and the insole and between the reinforcing piece and the outsole for bonding said parts together and stiffening the shank portion of the shoe bottom, and means for securing the outsole to the shoe in the forepart and heel portions thereof.

13. An open-shank shoe comprising an insole, a heel and shank reinforcing piece located beneath the insole and having a plurality of perforations in its shank portion, a two-part upper consisting of a forepart having its lower margin secured in overlasted position upon the insole and a back part having its lower margin secured in overlasted position upon said reinforcing piece, an outsole, a layer of hardened cementing and stiffening material between the insole and the shank portion of the reinforcing piece securing said parts together, a layer of said material between the reinforcing piece and the outsole securing said parts together, studs of said material filling the apertures in the reinforcing piece and integrally connecting said layers to provide a continuous body of said material stiffening the shank portion of the shoe bottom, and means for securing the outsole to the shoe in the forepart and heel portions thereof.

CERTIFICATE OF CORRECTION.

Patent No. 2,284,830.

June 2, 1942.

HORATIO S. LYNESS.

It is hereby certified that error appears in the printed specification of the above numbered patent requiring correction as follows: Page 4, first column, line 52, claim 9, strike out "said body also filling the alined perforations in" and insert the same after "together," in line 54, same claim; and that the said Letters Patent should be read with this correction therein that the same may conform to the record of the case in the Patent Office.

Signed and sealed this 4th day of August, A. D. 1942.

Henry Van Arsdale,
Acting Commissioner of Patents.
